Primary Examiner — Austin Murphy(74) *Attorney, Agent, or Firm* — Irina Hass(57) **CLAIM**

The ornamental design for a tape applicator, as shown and described.

DESCRIPTION

FIG. 1 is a perspective view showing the new design for a tape applicator;

FIG. 2 is a front view thereof, a rear view being a mirror image thereof;

FIG. 3 is a top view thereof;

FIG. 4 is a bottom view thereof;

FIG. 5 is a left side view thereof; and,

FIG. 6 is a right side view thereof.

The portions of the tape applicator shown in broken lines form no part of the claimed design.
